UNITED STATES PATENT OFFICE.

DAVID F. COGHLAN, OF HOLYOKE, MASSACHUSETTS.

UPRIGHT STEAM-BOILER.

SPECIFICATION forming part of Letters Patent No. 309,602, dated December 23, 1884.

Application filed September 23, 1882. (No model.)

To all whom it may concern:

Be it known that I, DAVID F. COGHLAN, a citizen of the United States, residing at Holyoke, in the county of Hampden and State of Massachusetts, have invented a new and useful Improvement in Upright Steam-Boilers, of which the following is a specification, reference being had to the accompanying drawings, forming a part thereof.

10 My invention relates to upright steam-boilers; and the object of my invention is to combine, with a central upright boiler placed over the fire-box, one or more supplementary boilers connected vertically with said central boiler and extending to the bottom of the fire-box, so that the heat may, after ascending through the flues of the central boiler, return through the flues of the supplementary boilers, and that that part of said supplementary boilers extending from the bottom of the central boiler to the bottom of the fire-box may be heated laterally and directly by the fire.

Figure 1 is a horizontal section of my invention with one supplementary boiler, in which A is the ash-pan. *a a a* are flues in the central boiler. *b b b* are flues in the supplementary boiler. C is the rear fire-wall. D is the door of the fire-box. D' is the door of the ash-pan. E is a hot-air chamber. H H are hand-holes for the purpose of cleaning the boiler of scale. I I is the lateral fire-wall. S is the central boiler, and S' is the supplementary boiler.

Fig. 2 is a vertical section of Fig. 1, in which *c c* are holes connecting the boilers S and S'. G is the grate of the fire-box. B is a bonnet covering the boilers S and S', and *h* are handles thereon.

Fig. 3 is an elevation of my invention.

40 Fig. 4 is a horizontal section of my invention with two supplementary boilers, S² and S³.

Fig. 5 is a vertical section of my invention with two supplementary boilers.

In upright steam-boilers heretofore made, in which the heat is used twice—that is, in which the heat is drawn downward through return-flues after having ascended through the flues from the fire-box—ascending and return flues have been built in the same boiler, no portion of which projects downward beyond the top of the fire-box. In my invention the return-flues are set in supplementary boilers, presenting a greater surface to the returning heat, and the supplementary boilers, projecting down beyond the bottom of the central boiler to the bottom of the fire-box, present such projecting surface to the fire directly.

By reference to Figs. 2 and 5 it will be seen that the boiler S sets directly over the fire-box, the heat from which ascends through the flues *a a*, and, returning in the direction indicated by the arrows, passes downward through the flues *b b* in the supplementary boilers, whence it again ascends to the chimney. The 60 supplementary boilers S' in Fig. 2 and S² and S³ in Fig. 5 project downward beyond the bottom of the boiler S, and that portion of said supplementary boilers so projecting is heated directly by the fire in the fire-box F. 70

I claim as my invention—

The combination of a furnace or fire-box, a main upright boiler arranged over the same, and one or more auxiliary boilers extending below the body of said main boiler and closely fitting around the latter, the water-spaces of the said main and auxiliary boilers being separated only by single shell, which is provided with openings at different levels, to permit of the free circulation of the water, substantially as set forth.

DAVID F. COGHLAN.
